[57] CLAIM

The ornamental design for a bowling bag shuttle cart, as shown and described.

DESCRIPTION

FIG. 1 is a top and rear perspective view of a bowling bag shuttle cart showing my new design; the broken lines are for illustrative purposes only and form no part of the claimed design;

FIG. 2 is a top plan view thereof;

FIG. 3 is a right side elevational view thereof, the left side elevational view being a mirror image of that shown;

FIG. 4 is a rear elevational view thereof;

FIG. 5 is a bottom plan view thereof; and

FIG. 6 is a front elevational view thereof.

*FIG. 4**FIG. 5**FIG. 6*
